BOILER CONSTRUCTION

William J. McAllister, Oak Park, Ill.

Application December 31, 1937, Serial No. 182,788

3 Claims. (Cl. 122—154)

This invention relates to boilers and more specifically relates to all-steel water tube boilers having streamlined, tear-drop type water tubes.

The boilers of this invention are especially adapted for domestic heating and can be fired with gas, oil, coal, or any other fuel. The combustion chamber provided by the boiler construction of this invention is readily adapted to receive any type of firing means and therefore the boiler construction has universal application.

The boilers of this invention comprise nested shells defining water legs entirely surrounding the combustion chamber. A baffle, of hollow construction, is provided in the combustion chamber and has the interior thereof in communication with the water legs between the nested shells. A smoke outlet is provided at the rear of the combustion chamber behind the baffle. Water tubes extend through the combustion chamber above the baffle therein and are welded at their ends to the inner shell to communicate with the spaces between the shells.

These water tubes are streamlined to have extensive contact with flames passing therearound. The flames travel from the fuel bed or burner head in front of the baffle upwardly around the water tubes, over the baffle and down to the smoke outlet. This sinuous path of the flames makes possible extensive contact with the water tubes and with the inner shell thereby effecting good heat transfer between the flames and the water to be generated into steam. Since the flames travel downwardly to the smoke outlet which is spaced behind the baffle, soot, fly ash or the like solids entrained with the flames can be deposited in a collection chamber provided between the baffle and the smoke outlet. As a result, such solid materials will not be discharged through the stack.

The streamlined water tubes, besides providing for extensive contact between the flames and the tubes to effect a good heat transfer, are also self-cleaning since soot, fly ash or the like solids carried by the flames will slide off of the tubes because of their streamlined contour and the lack of a surface on which to collect.

It is then an object of this invention to provide boiler constructions having streamlined tubes for effecting good heat transfer between the heating media and the material to be heated.

Another object of this invention is to provide boiler constructions having streamlined water tubes extending through the combustion chambers thereof.

A further object of this invention is to provide a combustion chamber for boilers that is entirely surrounded by water.

Another object of this invention is to provide a hollow baffle in combustion chambers of boilers in communication with the water space of the boiler.

A further object of this invention is to provide an all-steel boiler construction composed of nested inner and outer shells defining water spaces entirely around the combustion chamber of the boiler and having streamlined water tubes in communication with said spaces extending across the combustion chamber.

Another object of this invention is to provide in a boiler construction a natural trap for solid material entrained in gases leaving the boiler.

Other and further objects of this invention will become apparent to those skilled in the art from the following detailed description of the annexed sheet of drawings which discloses a preferred embodiment of the invention.

On the drawing:

Figure 1 is an isometric view of a boiler according to this invention, with parts broken away and shown in cross section to illustrate the construction of the boiler.

Figure 2 is an enlarged fragmentary cross-sectional view taken along the line II—II of Figure 1.

Figure 3 is a fragmentary cross-sectional view taken along the line III—III of Figure 1.

Figure 4 is a diagrammatic view showing flame contact with a streamlined water tube according to this invention as compared with a cylindrical water tube.

As shown on the drawing:

In Figure 1 the reference numeral 10 designates a boiler comprising outer, front and rear vertical steel plates 11 and 12 having arcuate top portions 13. An outer crown sheet 14 is welded at its ends to the plates 11 and 12 and forms with the plates the outer shell of the boiler. This shell is preferably composed of ordinary tank steel.

A second pair of smaller vertical steel plates 15 and 16 having arcuate top portions 17 is mounted in spaced opposed relation to the outer plates 11 and 12. The plates 15 and 16 terminate above the bottoms of the plates 11 and 12 and have outturned flanges such as 18 along their bottom edges. These flanges 18 are welded to the plates 11 and 12 respectively.

A crown sheet 19 extends between the plates 15 and 16 and is welded to the plates at its ends.

The crown sheet 19 has outturned flanges 20 along the bottoms thereof which flanges are welded to the sides of the outer crown sheet 14.

The inner plates 15 and 16 together with the inner crown sheet 19, define the inner shell of the boiler. This inner shell is in spaced relation from the outer shell and provides a water chamber 21 entirely surrounding the combustion chamber 22 of the boiler. This chamber 21 is composed of a front water leg 21a between the plates 11 and 15, a rear water leg 21b between the plates 12 and 16, side water legs 21c between the sides of the crown sheets 14 and 19, and a top water leg and steam space 21d between the tops of the crown sheets 19 and 14.

The inner shell is preferably composed of flange steel.

A hollow vertical baffle 23 is mounted in the combustion chamber 22 and has the interior thereof in communication with the water legs 21c at the sides of the boiler. The baffle 23 is welded to the sides of the inner crown sheet 19 and thus provides a further water leg 24 in the combustion chamber 22.

The baffle 23 is mounted intermediate the front and rear inner plates 15 and 16.

The top 25 of the baffle 23 is spaced below the top of the crown sheet 19.

A plurality of streamlined water tubes 26 extend horizontally through the combustion chamber 22 above the top 25 of the baffle 23 and are welded at their ends through the end plates 15 and 16, so that the interiors of the tubes communicate with the water legs 21a and 21b respectively.

As best shown in Figure 2, the tubes 26 are in staggered relation and are spaced to baffle the flow of flames and gases therearound.

The rear plates 12 and 16 have aligned openings 27 and 28 therethrough intermediate the tops and bottoms of the plates behind the baffle 23 and preferably below the top of the baffle. A collar 29 is welded in the openings 27 and 28 and extends between the plates. The collar 29 is adapted to receive the end of a flue pipe 30 therein. This construction provides a smoke outlet for the combustion chamber 22.

The inner and outer front plates 15 and 11 have large openings 31 therethrough above the flange 18 of the inner plate. A steel ring 32 is welded between the openings 31 to the plates. This construction provides a port to the combustion chamber 22 which port can be closed by a fire door 33.

In the embodiment of the invention shown in Figure 1 an oil burner head 34 is mounted in the combustion chamber in front of the baffle 23. The lower portion of the combustion chamber around the burner head 34 can be insulated with fire bricks such as 35.

The oil supply line 36 can extend into the combustion chamber 22 through an opening 37 cut in the bottom of the front plate 11.

It should be understood, however, that the combustion chamber 22 can receive any type of heating means such as a gas burner, a stoker, or a grate. An important feature of this boiler is the provision of a combustion chamber 22 adapted to receive any type of heating means. Of course, various fire brick arrangements can be used without in any way changing the boiler construction.

Flanged openings such as 38 are formed through the outer shell to receive inlet and return pipes (not shown) or clean out plugs (not

shown). The top of the crown sheet 14 contains a steam outlet 39.

In accordance with good boiler practice, the water level is maintained above the crown sheet 19 but below the steam outlet 39.

The lower portion of the combustion chamber behind the baffle 23 provides a natural trap for soot, and fly ash. Since the flames travel upwardly from the burner head or fuel bed, around the boiler tubes 26, over the baffle 23 and downwardly to the smoke outlet 30, entrained solid material can be collected in the space behind the baffle 23. A clean out door 40 is provided on the crown sheet 14 at the bottom thereof for cleaning out this space.

As best shown in Figure 4 the flames 41 in the combustion chamber will flow around a streamlined tear-drop type boiler tube 26 to be in extended contact with the tube over almost the entire exterior area thereof. In other words the flow of the flames as shown in dotted lines around the boiler tube 26 follows the contour of the tube. This extended contact between the flames and the boiler tube gives an excellent heat transfer for heating water in the tube.

On the other hand the commonly used cylindrical type tube, indicated by the reference numeral 42, can only contact the flames 41 around the lower half thereof.

Therefore the streamlined boiler tubes used in the construction of this invention are more efficient heat exchangers than ordinary cylindrical or other non-streamline shaped tubes.

It should be noted also that the top portions of cylindrical tubes provide surfaces for the collecting of soot, fly ash and the like. These surfaces are entirely dispensed with in the streamlined tubes. As a result, the boilers of this invention are substantially self-cleaning whereas heretofore it has been necessary to clean the water tubes of boilers at frequent intervals.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. A boiler construction comprising spaced opposed front and rear outer plates, an outer metal sheet welded to the tops and sides of said outer plates, front and rear inner plates each spaced from their cooperating outer plates to define water legs therebetween at the ends of the boiler, an inner metal sheet welded to the tops and sides of said inner plates and spaced from the outer metal sheet to define therewith a water space on the top and water legs on the sides of the boiler, said inner plates having a plurality of tear-drop shaped apertures therethrough near the tops thereof, a plurality of tear-drop shaped boiler tubes secured at their ends in said apertures to be in full communication with the water legs, a hollow baffle extending transversely between the sides of the inner metal sheet having the interior thereof communicating with the water legs at the sides of the boiler, the top of the baffle being below the top of the inner metal sheet, a smoke outlet at the rear of the boiler in spaced relation behind said baffle at a level intermediate the top and bottom of the baffle, the rear inner plate and rear wall of the baffle defining with the inner metal sheet a fly ash chamber and a door giving access to said chamber.

2. A boiler construction comprising spaced opposed front and rear outer plates, an outer metal sheet secured to the tops and sides of said outer plates, front and rear inner plates each spaced from their cooperating outer plates to define water legs therebetween at the ends of the boiler, an inner metal sheet secured to the tops and sides of said inner plates and spaced from the outer metal sheet to define therewith a water space on the top and water legs on the sides of the boiler, said inner plates having a plurality of tear drop shaped apertures therethrough, a plurality of tear drop shaped boiler tubes secured at their ends in said apertures to be in full communication with the water legs, a baffle extending transversely between the sides of the inner metal sheet in spaced relation from the front and rear inner plates, said baffle terminating below the top of the inner metal sheet, a smoke outlet at the rear of the boiler in spaced relation behind said baffle and communicating with the interior of the boiler at a level intermediate the top and bottom of the baffle, said rear inner plate and rear wall of the baffle defining with the inner metal sheet, a fly ash chamber, and clean out means giving access to said fly ash chamber.

3. A boiler construction comprising spaced op-

posed front and rear outer plates, an outer metal sheet secured to the tops and sides of said outer plates, front and rear inner plates each spaced from their cooperating outer plates to define water legs therebetween at the ends of the boiler, 5 an inner metal sheet secured to the tops and sides of said inner plates and spaced from the outer metal sheet to define therewith a water space on the top and water legs on the sides of the boiler, said inner plates having a plurality 10 of apertures therethrough, a plurality of water tubes secured at their ends in said apertures to be in communication with the water legs, a hollow baffle extending transversely between the sides of the inner metal sheet in spaced relation 15 from the front and rear inner plates and having the interior thereof communicating with the water legs at the sides of the boiler, the top of the baffle being below the top of the inner metal sheet, a smoke outlet at the rear of the boiler 20 in spaced relation behind said baffle and communicating with the boiler at a level intermediate the top and bottom of the baffle, said rear inner plate and the rear wall of the baffle defining with said inner metal sheet a fly ash chamber and a 25 clean out means giving access to said chamber.
